(57) **CLAIM**

The ornamental design for a mounting support for vertical bicycle rack, as shown and described.

DESCRIPTION

FIG. 1 is a perspective view of the mounting support for vertical bicycle rack of the present invention;

FIG. 2 is an enlarged front elevational view thereof;

FIG. 3 is an enlarged right side elevational view, the left side elevational view being a mirror image thereof;

FIG. 4 is an enlarged rear elevational view thereof;

FIG. 5 is an enlarged top plan view thereof; and,

FIG. 6 is an enlarged bottom plan view thereof.

The broken lines shown are for illustrative purposes only and form no part of the claimed design.
